STEAM TRAP GOVERNOR

Bert Swift, Tulsa, Okla.

Application June 18, 1943, Serial No. 491,356

1 Claim. (Cl. 251—121)

The invention relates to a governing means interposed between a steam trap and a steam line in which condensation accumulates, particularly in long steam lines and has for its object to provide a governor which will reduce the steam pressure in the steam trap, thereby allowing the valve float to re-seat if the valve is held against reseating incident to steam pressure in the steam trap, consequently loss of steam through the steam trap, incident to the sticking of the float, is obviated.

A further object is to provide a steam governor for steam traps comprising a casing having a partition therein forming two chambers, a ball valve within one of the chambers and cooperating with a seat on the down stream side, and the partition with a large port through which condensate and steam normally passes without seating the ball valve. Also to provide the partition with a bypass small port, through which steam pressure passes when the ball is seated so that a reduced pressure will result in the steam trap and relieve the high pressure on the float, which float is stuck against downward movement incident to the inrush of steam into the steam trap, thereby allowing the float controlled valve to be seated.

The pressure builds up on the down stream side of the partition and in the steam trap, thereby allowing the ball valve to unseat for normal operation of the device.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a longitudinal sectional view through the governor and trap, showing the steam line in transverse section.

Figure 2 is a longitudinal sectional view through the governor, showing the ball valve unseated.

Figure 3 is a view similar to Figure 2, showing the ball valve seated for reducing the pressure on the down stream side of the governor partition.

Referring to the drawing, the numeral 1 designates a steam line in which condensate accumulates incident to long runs of pipe. The steam line 1, at spaced intervals, is provided with downwardly extending chambered water legs 2, to each of which the device hereinafter set forth is at-

tached, however for purposes of illustration one trap and governor is shown.

Extending outwardly from the water leg 2 is a pipe line 3 having a master valve 4 and a control valve 5 therein. This is conventional structure. In devices at present constructed the pipe line 3 leads directly to the steam trap casing 6, and in the chamber of which the condensate accumulates until the float 8 is raised by its buoyancy between the guide fingers 9 for unseating the needle valve 10, which cooperates with a valve seat 11. This structure is old in the art. It has been found that there is a great loss of steam to the atmosphere caused by the float 8 becoming stuck in open position, incident to the steam pressure in the chamber 12 of the steam trap, and to obviate this difficulty the governor is provided between the water leg and the steam trap casing.

The governor comprises an elongated casing 13 having an upstream chamber 14 and a downstream chamber 15. Chambers 14 and 15 are formed by a transverse partition 16, one side of which is provided with a chambered extension 17 in the chamber 18 of which is a ball valve 19. Ball valve 19 cooperates with a valve seat 20 for closing a port 21 in communication with the down stream chamber 15. Under normal operation the steam and condensate pass from the pipe line 3 into the chamber 14 and thence through a large port 22 in the partition 16 to the chamber 18, thence around the ball valve 19 and through the port 21 without seating the valve 19 to the steam trap chamber 12. When the condensate accumulates in the steam trap the float 8 moves upwardly incident to its buoyancy and the condensate is then discharged through the discharge port 11. When the liquid level drops in the steam trap the valve 10 is again seated until the liquid level again builds up in the trap.

It has been found that sometimes there is an inrush of excessive amounts of steam into the steam trap during a liquid discharge operation and this steam pressure will force the float 8 upwardly above its normal range of operation and will cause the float to be stuck or frictionally held against the guides 9. So long as the steam trap works normally, that is intermittently dumping the water through an unseating and seating operation of the needle valve and during said operation the ball valve 19 remains unseated and the normal flow of steam continues to push out the water in the bottom of the steam trap, the steam and water will flow around the ball through the port 21 to the trap. However when

the float remains up and the needle valve unseated, incident to the inrush of excessive steam to the trap and sticks or holds the float, there will be a lowering of pressure in the steam trap and an exhaust of steam to the atmosphere through the trap, which exhaust will eventually permit the float 8 to drop and seat the valve. When the valve is again seated and the flow of steam to atmosphere stopped the pressure on each side of the valve and partition will be equalized by the passage of steam through port 23, and when this happens the ball valve will again drop or seat to the position shown in Figure 2 for normal operation of the device. So long as the differential of pressure on each side of the partition 16 is not too great the ball will remain off-seat and allow the steam trap to operate normally. The sticking or pressure holding of the float in raised position is caused by the rush of steam to atmosphere, thereby forcing the ball onto its seat. When this great rush of steam is stopped, by the seating of the ball valve the float will be released and the valve will seat and the only pressure that can reach the trap is that which flows through the small port 23, and this flow is much less than that which is capable of flowing out of the valve port in the steam trap, hence the float will be released from the steam pressure and the valve will again seat, and the pressure will again build up or equalize on both sides of the partition 16, and then the valve 19 will unseat and again assume its position as shown in Figure 2.

The governor casing 13 is provided with a filter screen 24 for preventing the passage of rust from the pipe line or foreign matter to the steam trap, hence this foreign matter gathers in the up-

stream chamber 14 and may be drained therefrom from time to time by opening the drain valve 25.

From the above it will be seen that a governor is provided for a steam trap in connection with a steam line which will reduce the pressure in the steam trap and release the float which controls the valve in the steam trap, thereby resuming the normal operation of the float, and preventing excessive loss of steam.

The device is particularly adapted for use in connection with relatively long steam lines, and it is obvious the device will eliminate the necessity of servicing the various steam traps carried by the line to prevent excessive loss of steam.

The invention having been set forth what is claimed as new and useful is:

An excess flow valve device comprising a casing having an enlarged central portion, a transverse partition in said enlarged portion spaced from the ends thereof and dividing the same into an enlarged upstream chamber and an enlarged down stream chamber, a horizontally disposed chambered valve cage carried at one end by said partition and entirely supported thereby and extending horizontally into the down stream chamber, a ball valve in said cage cooperating with a port in the free end of said valve cage, said ball having a rolling contact bearing on the bottom of the chamber of the cage, a port for admitting fluid to the valve cage chamber through the partition, means for admitting fluid from the upstream chamber to the down stream chamber through the partition above the valve cage said ports of the cage and partition being below the axis of the casing.
